G. A. COLLIER

PUMP

Filed June 11, 1919

Fig. 2.

UNITED STATES PATENT OFFICE.

GEORGE ALBERT COLLIER, OF NOTTINGHAM, ENGLAND.

PUMP.

Application filed June 11, 1919. Serial No. 303,443.

To all whom it may concern:

Be it known that I, GEORGE ALBERT COLLIER, a subject of the King of Great Britain, residing at 11 Hawksworth Road, West 5 Bridgford, in the city of Nottingham and county of Nottinghamshire, England, have invented new and useful Improvements in and Relating to Pumps, of which the following is a specification.

10 My invention relates to improvements in pumps fitted with a piston which is reciprocated by means of one or more cams. In this type of mechanism as applied to a valveless pump it has been proposed to provide a 15 helical groove in the piston and rotate it in conjunction with a stud and roller fastened to the cylinder, and in an apparatus for measuring and delivering liquids it has been proposed to use a piston which made a quarter 20 of a revolution and was reciprocated within the cylinder by means of a cam slot in the piston and pins in the cylinder.

The present invention has for its object 25 the production of a pump in which the piston is reciprocated by cams or rollers on the piston, and rollers or cams carried by plates or arms which are rotated within the outer diameter of the piston, which piston may be held stationary or rotated, also improvements 30 in the general arrangement and construction of the pump.

In the accompanying drawing:—

Fig. 1 is a sectional elevation of a pump with a rotating piston reciprocated by edge 35 cams.

Fig. 2 is a sectional elevation of a pump with a rotating piston reciprocated by a rotating box cam, and

Fig. 3 is a sectional elevation of a pump 40 with a rotating piston reciprocated by rotating edge cams.

In the pump shown in Fig. 1 there is a cylinder 1 with a closed end 2 and a cover 3, or there may be covers at both ends, and 45 each cover is or may be provided with a gland and stuffing box, also the cylinder is provided with inlet valves 4 and outlet valves 5 and such valves may be of any suitable type and may be arranged in any convenient 50 positions upon the cylinder. Inside the cylinder there is a piston 13. This piston is mounted upon a central shaft 14 to which it is connected in such manner that it rotates therewith and yet is free to slide thereon. 55 The piston is provided, upon opposite sides or faces of the web or plate 10 that unites

the piston rim with the shaft 14, with a pair of one or more throw, edge cams 15, which are inside of and concentric with the peripheral rim of the piston. Bearing upon the 60 edges of these cams are rollers 16 carried by the non-rotating arms or disks 17, which are represented as being secured to the pump casing by bolts 36.

In the pump shown in Fig. 2 there is a 65 cylindrical pump casing 18 with inlet valves 19 and outlet valves 20. In this arrangement the piston 21 is carried by a shaft 22 and rotates with such shaft and also slides on or with such shaft. Inside the piston there is a 70 one or more throw box cam 23 with which engage the rollers 24 carried by arms 25 mounted upon a rotating shaft 26 which is held from end movement. In this arrangement the shafts 22 and 26 may be rotated in 75 the same direction but at different speeds, or the shafts may be rotated in opposite directions at the same or different speeds.

In the pump shown in Fig. 3, the piston 27 is shown with a one throw edge cam 34 80 having opposite parallel edges or faces, but such cam may have two or more throws. The piston is mounted upon a central shaft 29 and is fitted to rotate with such shaft and to slide on or with the shaft. Working in 85 conjunction with the cam there are rollers 30 carried by arms 31 and 32. The arm 31 is carried by a sleeve 33 and the arm 32 by a shaft 35. The sleeve and the shaft 35 are held from end movement and, 90 when the pump is in operation, are caused to revolve in unison. In this arrangement the arms 31 and 32 may be rotated in the same direction as the piston but at a different speed, or the arms may be rotated in the opposite direction to the piston at the same or a different speed.

The pump shown in Fig. 1 may have the cylinders fitted with two or more pistons and the arrangement of the inlet and outlet 100 valves and of the cams and rollers bearing thereon are modified accordingly.

In addition to the parts herein described, the shafts may be fitted with ball or other end thrust bearings and the pumps with 105 other usual and necessary parts.

It will be observed that in each of the embodiments of my invention illustrated in the drawings and described, the means employed for effecting reciprocations of the piston, 110 which means include cams and co-operating abutments or bearings, in the form of trucks

or rollers employed to reduce friction,—are arranged entirely within the peripheral face of the piston, thus making it possible to utilize the full face of the piston in the pumping operations. One of the said co-operating, piston-reciprocating, elements, which one—so far as the broad features of my invention are concerned,—is immaterial, is carried by the piston and hence reciprocates therewith, while the other element is held against corresponding reciprocation. Likewise, one of these elements rotates with the shaft that enters the pump casing, while the other element is held against corresponding rotation. It follows that there may be a reversal of location of the piston reciprocating elements of the pump, and this has been illustrated by means of the several embodiments of my invention presented in the drawings. Each particular embodiment herein shown is capable of modification along the lines indicated, but in order to not require an unnecessarily large number of drawings it is thought that the showing taken in connection with this specification indicates the extent to which the invention may be modified and still come within the scope of the invention and the claims which appear herein.

30 I claim:

1. A pump comprising a casing, a reciprocating piston fitting the casing, a cam carried by the piston, a rotating shaft to which the piston is secured so as to cause it to rotate therewith but leaving it free to reciprocate in the casing, another rotating shaft entering the casing, a roller bearing upon the said cam, carried by and rotating with the second mentioned shaft, and means for preventing longitudinal movements of the roller corresponding with the reciprocations of the piston, the shafts being adapted to have differential rotations imparted to them.

45 2. A pump comprising a casing, a reciprocating piston fitting the casing, a cam carried by the piston having two opposite faces

parallel with each other, a rotating shaft to which the piston is secured so as to cause it to rotate therewith but leaving it free to reciprocate in the casing, rollers bearing upon the said opposite faces of the cam, and rotating shafts entering the casing from opposite sides and carrying the said rollers, these shafts being held against longitudinal movement and being adapted to be rotated in unison, and the shaft carrying the piston being adapted to have a rotative movement that is not in unison with the shafts carrying the rollers.

60 3. The combination stated in claim 1, having the piston reciprocating elements, comprising cam and co-operating rollers, located entirely inside a cylinder generated about the axis of the shaft carrying the piston and whose surface includes the peripheral face of the piston.

4. The combination stated in claim 2, having the piston reciprocating elements—comprising cam and co-operating rollers—, located entirely within a circle including the peripheral face of the piston.

5. A pump comprising a casing, a reciprocating piston having a peripheral rim portion fitting the casing and a web uniting it with a rotating shaft, a pair of edge cams extending respectively from the opposite faces of the web of the piston and inside of and concentric with the peripheral rim thereof, rollers upon opposite sides of the piston bearing upon the edges of the said cams and co-operating therewith to effect longitudinal reciprocation of the piston, means for rotating one of the co-operating means that effects reciprocations of the piston, and means for holding the rollers against longitudinal movement.

In witness whereof I have signed this specification in the presence of two witnesses.

Dated this 26th day of May, 1919.

GEORGE ALBERT COLLIER.

Witnesses:

E. M. POTTER,
ARTHUR MORLEY.
